US00D654806S

(12) **United States Design Patent**
Lorenz et al.(10) **Patent No.:** **US D654,806 S**
(45) **Date of Patent:** **** Feb. 28, 2012**

- (54) **SPRAY DISPENSING CONTAINER**
- (75) Inventors: **Mike Lorenz**, Gahanna, OH (US);
Nathan D. Durflinger, Youngstown, OH (US)
- (73) Assignee: **R. J. Reynolds Tobacco Company**, Winston-Salem, NC (US)
- (**) Term: **14 Years**
- (21) Appl. No.: **29/387,236**
- (22) Filed: **Mar. 10, 2011**
- (51) **LOC (9) CL. 09-01**
- (52) **U.S. CL. D9/687**
- (58) **Field of Classification Search** D9/682-694, D9/516-575, 434-455, 723-729; D28/5, D28/76, 77, 91.1; 222/129, 135, 153.01, 222/153.03, 153.04, 153.09, 153.11-153.14, 222/182, 631, 635, 209, 211-213, 215, 321.7-321.9, 222/372, 373, 378, 379, 383.1, 384-386, 222/398, 400.7, 400.8, 401, 402.1-402.25; D24/108, 110, 110.5; 128/200.12, 200.14, 128/200.17-200.23, 203.12-203.24; D27/139, D27/141-161, 172, 183-194
